UNITED STATES PATENT OFFICE.

FRANCIS P. MCCOLL, OF BROOKLYN, NEW YORK, ASSIGNOR TO THE FRANCO-AMERICAN PATENT CAN OPENING COMPANY, OF NEW JERSEY.

METAL CAN.

SPECIFICATION forming part of Letters Patent No. 570,494, dated November 3, 1896.

Application filed October 18, 1895. Serial No. 566,049. (No model.)

To all whom it may concern:

Be it known that I, FRANCIS P. MCCOLL, of the city of Brooklyn, county of Kings, and State of New York, have invented certain new and useful Improvements in Metal Cans, &c., of which the following is a specification, reference being had to the accompanying drawings, forming a part hereof.

This invention relates to cans or other receptacles, formed of sheet metal or other like material, which are intended to contain meats, fish, vegetables, paints, or other substances, and usually require to be sealed hermetically, and it is particularly concerned with the method of or means for opening such cans or receptacles. Such cans or their covers have heretofore been constructed in many different ways with a view to facilitating the opening thereof, and many different devices have been applied to cans for the same purpose. A usual method of opening such cans or receptacles is by tearing the cover along predetermined lines. This is an easy and effectual method, but is not desirable for some purposes on account of the incision made in the cover to receive the end of the starting-tongue, which incision, although soldered or cemented, is a frequent cause of leakage. In no case, moreover, has it been directly sought, so far as I am aware, to preserve the cover or removed portion of the can or receptacle in such shape that it could be applied again to the can or receptacle or body thereof, so that the unused portion of the contents could be protected for the time being from exposure to the air, insects, dust, or other extraneous matter. On the contrary, the cover or removed portion of the can has been cut or torn or twisted or otherwise left in such shape as to be incapable thereafter of application to the can to effectively shut out air, dust, or insects. Realizing the defects which are here alluded to, I have sought to provide not only for the easy opening of cans of the class referred to without necessitating an incision in any portion of the cover in contact with the contents of the can, but for the preservation of the cover or removed portion of the can in such shape that it may be applied again to

the opened can and protect its contents, as well as for the preservation of the can-body without mutilation.

The invention is capable of application to cans or receptacles of great variety as to form and construction; but in the accompanying drawings, which form a part hereof, I have chosen for illustration of the invention certain common forms.

In the drawings, Figure 1 is a view in perspective of an ordinary round can to which my invention is applied, the cover being represented as detached from the body of the can, so that certain features of construction may be clearly seen. Fig. 2 is a similar view, but with the two parts of the can—that is to say, the body and the cover—assembled and an opening-key applied to the starting-tongue. Fig. 3 is a view similar to Fig. 2, but representing the can as partly opened. Fig. 4 is a detail view of a portion of a can-body such as is represented in Fig. 1, but showing a slight modification. Fig. 5 is a perspective view of a generally rectangular can or box in which the cover is soldered or cemented upon an inwardly-turned flange of the body, portions of the cover and of the body being broken out to show the construction more clearly. Fig. 6 is a similar view of a can or box of like shape, but with the cover differently applied to the body. Figs. 7 and 8 are detail views illustrating the formation of the starting-tongue with the cover-blank. Fig. 9 is a perspective view of a can of like shape to that shown in Fig. 5, but having a cover with a downwardly-turned overlapping flange. Fig. 10 is a view similar to Fig. 7, but illustrating a slight difference in construction. Fig. 11 is a detail view of a portion of the can-body shown in Figs. 9 and 10 and illustrating a feature of construction. Fig. 12 illustrates a further feature of construction.

It will be understood that the invention finds expression in all of the different forms represented in the several figures of the drawings, and it will be observed that all of these forms have certain common characteristics, such as that the can is made up of two parts, comprising a body and a cover or removable

portion, that the two parts of the can overlap, and that a starting-tongue projects from between the two overlapping portions.

Having thus indicated the general features of the cans shown, in order that the following description may be the more readily understood, I will now proceed to describe in detail the particular construction of each of the different forms represented.

- 10 Referring first to the can shown in Figs. 1 to 4, it will be observed that it comprises a body A, formed in any suitable way, and a slip-cover B, having a depending flange b, which may be slipped upon (or, it may be, within) the body A. The flange b, or overlapping portion of the cover, is soldered or cemented to the corresponding portion of the body A, and in the particular form here represented is scored or otherwise weakened along a predetermined line, as indicated by the dotted line b', which line indicates the extent of the overlap and corresponds or coincides with the edge of the can-body A. As the overlapping portions of the body and cover are soldered or cemented together only between the edge b² of the outer portion and the line b', it will be observed that the lines b' and b² may both be termed "predetermined lines of weakness," along which, as will presently appear, the separation between the two parts of the box takes place. At any convenient point along the line b² an opening-tongue C projects from between the two overlapping portions of body and cover. This tongue may be disposed differently, according to the particular form of the can or the use to which it is to be put, but as represented in the form now under consideration it projects outwardly through an incision b³, formed in the cover B, but extending through or nearly through the overlapping portion only of such cover, so that there shall be no incision through any portion of the cover which is in contact with the contents of the box. Moreover, as this incision is formed only in that portion of the cover which is soldered or cemented to the body it does not constitute a weak place in the sealed box. The tongue C should be secured by solder or any other suitable means to the inner side of the outer of the two overlapping portions or between said overlapping portions, that is to say, in the construction represented, to the inner surface of the overlapping portion of the cover B, or between the two overlapping portions, and it projects outwardly through the incision b³. For convenience in manufacture the tongue may be attached to the body of the box and be secured to the inner side of the overlapping portion of the cover in one operation when the latter is soldered upon the body.

As indicated in Fig. 1, the tongue is formed in a separate piece and is lightly soldered to the body of the box, its inner end being cut off obliquely and matched with a correspondingly-formed portion of the outer overlapping edge of the box-body, the purpose of

this construction being simply to avoid an undue thickness. The tongue C is preferably, however, formed in one piece integral with the box-body, as indicated in Fig. 4, and weakened along a line c', so that it may separate readily from the box-body when the box is being opened. It is not, however, deemed essential that there should be any line of weakness between the box-body and the tongue, inasmuch as without it the tongue is readily separable from the body and would generally tear off from the body without mutilating the latter to any material extent. If the tongue is integral with the body or cover or otherwise, it is preferably located at such a point that it shall have a backing to be left to maintain the integrity of the box below its upper edge when the tongue is torn off, the usual lap-seam being well adapted for such purpose.

In opening the box, which has been described, the tongue C is grasped by the fingers or by any suitable tool, but preferably by a key, such as is shown at D, and is pulled backward upon itself, or, if the key be used, is rolled backward upon itself in the manner represented in Fig. 3. As the edges of the tongue correspond with or form continuations of the predetermined lines of weakness of the overlapping cover, and as the tongue is secured to the inner surface of the portion between these lines, it will, as it is pulled back or rolled back, bring with it the said overlapping portion of the cover, tearing it off from the body along the predetermined lines of weakness b' and b². As these two lines are parallel in the construction shown, and as the line b' coincides with the edge of the box-body, the cover will thus be released by the tearing off of a strip of uniform width, which leaves the cover in condition to be applied again to the box-body. The body itself, being unweakened and capable of resisting the tendency to tear as the strip is pulled off, will be left unmutilated below its upper edge and will therefore retain its contents without leakage.

It will be evident that if the flange of the cover were inserted within the edge of the box-body, so that the latter forms the outer of the two overlapping portions, the line of weakness b' would be formed in the box-body and would coincide with the edge of the cover, the tongue in every case being adapted to start up and tear off a strip of uniform width from the outer of the two overlapping portions, whether it be the box or the cover. It is also obvious that the tongue may be arranged to project between the overlapping ends of the cover or body blank and a separate incision be thereby dispensed with.

I find that a key or other tool may be wholly dispensed with if the tongue be so formed as to afford a firm grasp for the fingers and to avoid the danger of cutting the fingers. Accordingly I prefer to provide the tongue C with a finger-piece C', as shown in Fig. 12, the

edge of the finger-piece being crinkled, as shown at c^2 , which not only permits it to be firmly grasped by the fingers, but also obviates altogether any straight edge which might 5 cut the fingers.

In the form represented in Fig. 5 the box-body A is formed with an inwardly-turned flange a , upon which the flat cover B is secured directly. The one predetermined line 10 of weakness b' , which is formed by scoring or otherwise, coincides with the inner edge of the flange a , while the other predetermined line of weakness b^2 , or the edge of the cover, is flush with the sides of the box. The tongue C projects as before through an incision b^3 , which 15 is formed wholly in that portion of the cover soldered to the box-body. The opening of the can is performed in the same manner as that already described. It will be evident that in 20 this case the remaining portion of the cover after the box has been opened will be of substantially the same size as the opening in the box, and may therefore not be available to cover again the contents of the box. Never- 25 theless this form of box is desirable, because an incision through that portion of the cover which comes in contact with the contents of the box is avoided.

The body A of the can shown in Fig. 6 has 30 an inwardly-projecting bead a' , upon which the cover B may rest. When the cover has been put in place, a flange a^2 is turned down upon the cover and is soldered or cemented thereto, the outer of the two overlapping portions being in this case a part of the box-body. The inner edge a^3 of the flange a^2 is in this 35 case one of the two predetermined lines of weakness and the outer edge a^4 of the flange is the other, this edge substantially coinciding with the edge of the cover B. The tongue C is applied as before, projecting from between the overlapping portions and in this 40 particular case projecting through an incision a^5 , formed wholly within the outer overlapping portion and between the lines a^3 and a^4 , the edges of the tongue, as before, forming continuations of these lines and the tongue being secured to the undersurface of the outer overlapping portion. In opening this box the 45 overlapping portion of the body is torn off, leaving the cover intact and adapted to rest upon the bead a' and thereby protect the contents of the box.

In Fig. 6 the tongue is represented as independent of the box cover and body. As a 50 matter of economy in manufacture, however, it is preferable to form the tongue in the manner indicated in Figs. 7 and 8, the tongue being formed integral with the body or cover 55 blank, as shown in Fig. 7. The projecting piece b^4 , from which the tongue is formed, is bent over on the dotted line of Fig. 7 until it assumes the position shown in Fig. 8, and the tongue portion is raised that it may be 60 passed through the incision in the overlapping portion. When the box is opened, the

portion b^4 will tear off from the body or cover along the line of the fold.

In Fig. 9 I have shown a form of box similar to the form shown in Figs. 5 and 6, but 70 with a slip-cover B, having a depending flange b , substantially as in Fig. 1, and the adaptation of the invention to this particular form is calculated to avoid any incision through the cover of the box. The cover is provided 75 by scoring or otherwise with two predetermined lines of weakness b' and b^2 , which are brought out to the edge of the cover. The tongue C projects directly from between the overlapping portions of the cover and body, 80 with its edges in line with the predetermined lines of weakness b' and b^2 , the tongue being secured to the inner surface of the overlapping portion of the cover and being adapted to separate readily from the body A. A key 85 or other suitable tool being applied to the tongue C, the latter being rolled back upon itself, the box-cover will be torn upon the predetermined lines of weakness, and by continued rotation of the key may be wholly removed from the box-body, substantially as in 90 the manner set forth in Letters Patent of the United States granted to F. C. Busch September 25, 1894, and numbered 526,435. In this construction it is not even necessary that 95 the predetermined lines of weakness should be extended to the very edge of the cover nor that the bead be flattened to form a path for the starting up of the strip to be torn out, as indicated in Fig. 9; but, as represented in 100 Figs. 10, the lines b' and b^2 may terminate inside of the bead of the box and the latter need not be flattened or weakened, for the tongue C will tear through the edge of the cover until the lines of rupture, corresponding 105 with the edges of the tongue, meet the lines of weakness b' and b^2 . The tongue C may be formed independently of the box body or cover or it may be formed with the box-body, as indicated in Fig. 11, in which case 110 the tongue will tear off from the box-body in line with its edge.

From the foregoing description it will be obvious that the principle of the invention, whether its object be only to avoid an undesirable incision through the box-cover or to preserve the cover in such shape as to permit its use after removal or to prevent the mutilation of the can or box body, may be embodied in a great variety of forms. Accordingly I desire it to be understood that I 115 do not intend that my invention shall be limited to the forms and arrangements shown herein.

What I claim, and desire to secure by Letters Patent, is—

1. A can or receptacle having overlapping portions and a tongue or projection secured to the inner surface of the outer of said overlapping portions but readily separable from the other and passing from between the two portions, the can or receptacle having a backing 130

for said tongue or projection from which it may be torn without mutilating the can or receptacle, substantially as set forth.

2. A can or receptacle having overlapping portions secured together by cement or solder, the one of said parts which overlaps the other having predetermined lines of weakness and the other part being unweakened and capable of resisting the tendency to tear, in combination with a tongue projecting from between the overlapping portions and secured to the inner surface of the outer of said overlapping portions but readily separable from the inner portion and having its edges corresponding with said predetermined lines of weakness, substantially as set forth.

3. A can or receptacle having overlapping portions secured together by cement or solder, the one of said parts which overlaps the other having a predetermined line of weakness, substantially parallel with its edge and substantially coinciding with the edge of the inner portion and the other of said parts being unweakened and capable of resisting the tendency to tear, in combination with a tongue projecting from between the overlapping portions and secured to the inner surface of the outer of said overlapping portions but readily separable from the inner portion and having its edges corresponding respectively with the

edge of the overlapping portion and with the predetermined line of weakness in said portion, substantially as set forth.

4. A can or receptacle having overlapping portions secured together by cement or solder, the one of said parts which overlaps the other having a predetermined line of weakness, substantially parallel with its edge and substantially coinciding with the edge of the inner portion and having an incision formed wholly between said predetermined line of weakness and the edge of the overlapping portion, the other portion being unweakened and capable of resisting the tendency to tear, in combination with a tongue projecting from between the overlapping portions through said incision and secured to the inner surface of said overlapping portion but readily separable from the inner portion and having its edges corresponding respectively with said line of weakness and with the edge of the overlapping portion, substantially as set forth.

This specification signed and witnessed this 9th day of October, A. D. 1895.

FRANCIS P. MCCOLL.

In presence of—

ALFRED W. KIDDLE,
CHAS. EPWORTH.
